Primary Examiner — Sandra Morris(74) *Attorney, Agent, or Firm* — McAndrews Held & Malloy, Ltd.(57) **CLAIM**

The ornamental design for a packaging for sanitation gloves, as shown and described.

DESCRIPTION

FIG. 1 is a front right perspective view of packaging for sanitation gloves showing our design;

FIG. 2 is a left side elevational view thereof;

FIG. 3 is a right side elevational view thereof;

FIG. 4 is a front elevation view thereof;

FIG. 5 is a rear elevation view thereof;

FIG. 6 is a top plan view thereof; and,

FIG. 7 is a bottom plan view thereof.

The broken lines illustrating portions of a packaging are for environmental purposes only and form no part of the claimed design.
